O. BRUMBAUGH

SILO OR TANK

Filed Aug. 17, 1922

UNITED STATES PATENT OFFICE.

OLIVER BRUMBAUGH, OF LOUISVILLE, OHIO.

SILo OR TANK.

Application filed August 17, 1922. Serial No. 582,485.

To all whom it may concern:

Be it known that I, OLIVER BRUMBAUGH, a citizen of the United States, residing at Louisville, in the county of Stark and State 5 of Ohio, have invented a new and useful Silo or Tank, of which the following is a specification.

This invention relates to improvements in silo construction and particularly to a silo 10 built of hollow blocks of tile, although the invention is applicable to other structures comprising a wall of hollow tile such as tanks, well curbings and the like.

The objects of the invention are to provide 15 a construction of this kind including plaster locking clips by means of which the tile are firmly bound together in the wall; to provide brace rods extending across the doorway and entirely through the tile adjacent 20 to the doorway for securely bracing the structure; to move the door construction of the silo.

The above and ancillary objects may be attained by constructing the silo construction 25 such as illustrated in the accompanying drawing, in which—

Figure 1 is a fragmentary elevation of a silo;

Fig. 2, a section on the line 2—2, Fig. 1; 30 Fig. 3, a vertical, sectional view through a portion of the wall; and

Fig. 4, a detail perspective view upon an enlarged scale of one of the locking clips.

Similar numerals of reference indicate 35 corresponding parts throughout the drawing.

Referring to the accompanying drawings which show the invention embodied in a silo, the blocks of which the silo wall is built are indicated at 1, each of these blocks 40 being hollow and preferably of a height equal to its width; the blocks being preferably segmental in form, as best shown in Fig. 2, so that when they are assembled together, a circular wall will be formed.

In order to produce an extremely cheap, as well as durable construction, the blocks are preferably molded of clay and burned in the usual manner and provided with the vertical openings 2 to provide air spaces as well 45 as to lessen the weight of the blocks.

In building the wall, after the first tier of blocks has been properly arranged, the blocks are securely located together by 50 means of the locking clips 3 which are preferably formed of the same material as the

blocks, and adapted to be introduced over the upper edges of the meeting end walls of each pair of blocks, the channel 4 of each clip being of sufficient depth to allow the 60 depending edges 5 of the clip to extend a considerable distance along the inner faces of the end walls of the blocks, thereby forming a permanent lock for the blocks.

It will be understood, of course, that mortar or cement is placed between the end walls of the blocks and the clips 3 as indicated at 6 in Fig. 3, and attention is called to the horizontal grooves 7 formed in the depending inner faces of the clips, arranged 70 to receive the mortar and form a rigid bond between the blocks and clips.

After the locking clips are thus placed on the first tier of blocks, the next tier of blocks is placed in position and so arranged that 75 the side walls of the blocks in the two tier will meet midway of the length of the blocks in the first tier, as shown in Fig. 3, the lower ends of adjacent end walls of each 80 pair of blocks extending between the adjacent pair of clips 3, and raised upon the shoulders 8 of the clips, which preferably abut as illustrated. Mortar is preferably placed between each pair of clips and the lower end portions of the blocks in the two 85 tier as shown at 9.

Each succeeding tier of blocks is placed in position upon the next lower tier in the same manner, the clips being placed between the tiers of blocks as above described, it 90 being understood that the points between the ends of the blocks of each tier are to be staggered with relation to the points between the ends of the blocks in the adjacent tiers, as best shown in Figs. 1 and 3. 95

In silos it is necessary to provide a doorway such as indicated at 10, which extends from the bottom to the top of the structure. With the present construction, it is not necessary to provide a special frame for 100 the doorway, the blocks adjacent to the doorway upon each side forming the door jamb.

As the omission of the blocks to form the doorway will necessarily weaken the wall at this point, brace rods 11 are extended transversely across the doorway at intervals and are projected entirely through the blocks, forming the door jambs and through the adjacent walls of the next adjacent blocks as best shown in Fig. 2, washers 12 being placed upon the end portions 105 of the tie rods in engagement with the in-

ner walls of the blocks, nuts 13 being provided upon said brace rods for drawing the washers into tight engagement with the inner walls of the blocks.

- 5 Each door comprises a metal sheet 14 preferably having a rectangular, malleable frame 15 riveted or otherwise secured thereto for the purpose of reinforcing the door. In order to readily position the door sections within the doorway or remove the same therefrom, handle bars 16 are extended transversely across the door sections and secured to the frame 15 in any suitable manner. These handle bars, together with the 15 brace rods 11, provide a ladder by means of which the user may climb to the top of the silo.

Hooks 17 are provided at the upper portion of each door section and engage the 20 adjacent brace rod 11, securing each door section in place, each section being of greater width than the doorway, the longitudinal edges thereof extending beyond and engaging the rear faces of the blocks which form 25 the door jamb as shown at 18 in Fig. 2.

It will be seen that in view of the simplicity of this device, the structure may be very cheaply constructed and at the same time renders the same extremely strong and 30 durable. It will further be understood that although the invention is illustrated and described as applied to a silo, yet tanks,

such as water, oil or grain tanks, standpipes, well curbing, smokestacks, or walls for other structures may be built with the blocks and 35 clips embodying the invention.

With the use of these hollow blocks and clips, an ideal construction is produced which will stand an extreme outward pressure as each intermediate block is tied by 40 three clips to six other blocks, forming a bond between the blocks above, below and at each side thereof.

I claim:—

1. A structure of the character described 45 comprising the combination with a plurality of hollow blocks assembled together to form a wall of channel shaped clips located over the upper end portions of adjacent end walls of each pair of blocks, and provided with 50 shoulders to receive the lower end portions of adjacent end walls of the next tier of blocks.

2. A structure of the character described comprising the combination with a plurality of hollow blocks assembled together to form 55 a wall of channel shaped clips located over the upper end portions of adjacent end walls of each pair of blocks, and provided with shoulders to receive the lower end portions 60 of adjacent end walls of the next tier of blocks, the inner faces of said clips being grooved to receive a plastic bond.

OLIVER BRUMBAUGH.
